(57) **CLAIM**

The ornamental design for a framing member, as shown and described.

DESCRIPTION

FIG. 1 is a perspective view of a framing member in accordance with the present invention.

FIG. 2 is a top plan view thereof.

FIG. 3 is a bottom plan view thereof.

FIG. 4 is a front elevational view thereof.

FIG. 5 is a right side elevational view thereof.

FIG. 6 is a rear elevational view thereof.

FIG. 7 is a left side elevational view thereof.

FIG. 8 is a perspective view of a framing member of another embodiment in accordance with the present invention.

FIG. 9 is a top plan view thereof.

FIG. 10 is a bottom plan view thereof.

FIG. 11 is a front elevational view thereof.

FIG. 12 is a right side elevational view thereof.

FIG. 13 is a rear elevational view thereof.

FIG. 14 is a left side elevational view thereof.

FIG. 15 is a perspective view of a framing member of yet another embodiment in accordance with the present invention.

FIG. 16 is a top plan view thereof.

FIG. 17 is a bottom plan view thereof.

FIG. 18 is a front elevational view thereof.

FIG. 19 is a right side elevational view thereof.

FIG. 20 is a rear elevational view thereof; and,

FIG. 21 is a left side elevational view thereof.

The appearance of any portion of the framing member between the break lines shown forms no part of the claimed design. The broken lines are for the purpose of indicating break lines and form no part of the claimed design.

1 Claim, 14 Drawing Sheets
